MACHINE FOR BENDING TUBING

Stephen A. Tirone, Buffalo, N. Y., assignor to
Fedders-Quigan Corporation, Buffalo, N. Y.

Application August 3, 1951, Serial No. 240,075

3 Claims. (Cl. 153—46)

I

This invention relates to a machine for bending tubing, and it has particular reference to a machine for bending long lengths of tubing back and forth to form a serpentine coil in which the successive runs are closely spaced, and are interconnected by return bends of relatively small radius.

Serpentine coils are extensively used in the refrigeration industry as condensers and evaporators, and it is common practice to form them by reversely bending a length of straight tubing a sufficient number of times to provide the desired number of straight lengths or runs, which are successively connected to return bends of 180°. Bending machines are well known and commercially available for forming the coil by grasping it at an appropriate distance from one end and swinging the projecting portion around a die of circular cross section, thereafter advancing the tubing another increment, turning it over, and repeating the operation. A major problem has been to form these bends on relatively small radii without crushing, cracking, or otherwise damaging the tubing at the bend, or without so disturbing the tubing that the flow and performance characteristics of the finished coil are seriously impaired.

When the bending radius is large compared to the tube diameter, existing equipment can form 180° bends without intolerable distortion. For bending to a smaller radius, it has been proposed to insert a mandrel of some kind inside the tube, so that the metal wall could not collapse. This expedient, however, has not proved to be satisfactory. A metal mandrel must be positioned with great accuracy, and liquid or sand mandrels present subsequent cleaning problems. In any event, an internal mandrel alone is no guarantee against tube rupture, as the metal can crack from the inside out, as well as collapse when no mandrel is used. An additional disadvantage is, that in working relatively long lengths of tubing, say fifty to one hundred feet, the control and manipulation of any type of mandrel becomes a practical impossibility for large scale production operations.

According to the present invention, a swing type tube bending machine is provided, organized for operation on tubing without the employment of any internal mandrel or support, and by means of which tubing can be bent through arcs up to and over 180° on a small radius without serious distortion. As illustrative of the term "small radius," machines made in accordance with this invention form serpentine coils from copper clad steel tubing having 0.375 inch out-

2

side diameter with a bend radius of 0.50 inch, thus spacing the runs on one inch centers. Such tubing is somewhat difficult to work at best, presenting many more problems than copper tubing, because of the greater hardness and toughness of the steel. For refrigeration service, many engineering specifications limit the permissible distortion of the bend to twenty per cent reduction in cross sectional area, irrespective of the tube diameter or bend radius. Reduction of area in bends made on the present machine rarely exceeds ten per cent, and the nature of the deformation from true circular cross section, or "out-of-roundness," is such that the hydraulic or flow characteristics, and therefore pressure drop through the coil, are not seriously impaired.

This improved bending machine, as will hereinafter be described in detail, includes a rotatable bending block or die having a semicylindrical and grooved end around which the bend is formed. Clamping means are provided to secure the tubing to the block in advance of the bend, and a grooved follower plate is provided to engage the tubing, and force it into the end groove as the die is rotated. Mechanism is also provided to impose significant pressure on the follower plate during the movement of the die, and to release the pressure when the bend is completed, so that the tubing can be shifted for a subsequent operation.

The forming grooves in the die and follower plate, throughout the portions corresponding to the linear length of the bend, are not semicircular in cross section, but deviate therefrom into a somewhat semi-elliptical contour. Contrary to what might have been supposed, it has been found that if the tubing is gripped tightly around its entire circumference, and is slightly deformed into oval shape with the major axis parallel to the plane of adjacent runs, it may be bent around the forming die to form a smooth return bend having a small radius of curvature compared to the tube diameter, and that no internal mandrel is required to accomplish this result.

These features and advantages, together with others, will be made more apparent from the following detailed description of a typical embodiment of the invention, illustrated in the accompanying drawings, wherein:

Fig. 1 is a plan of the machine, with a partially formed serpentine coil shown in full lines at the start of a bending operation, and in broken lines at the completion thereof;

Fig. 2 is a front elevation, with portions of the table broken away;

Fig. 3 is a fragmentary side elevation;

Fig. 4 is a section taken substantially on the line 4—4 of Fig. 3, showing particularly elements of the pressure applying mechanism;

Fig. 5 is an enlarged section on the line 5—5 of Fig. 1 or 4;

Fig. 6 is an additionally enlarged horizontal section through the die block and follower, taken at the completion of a bending operation;

Fig. 7 is a still further enlarged section on the line 7—7 of Fig. 6;

Fig. 8 is a section through a tube bend, along the line 8—8 of Fig. 6;

Fig. 9 is a perspective of a cam control member for the pressure applying mechanism; and

Fig. 10 is an exploded perspective of two of the elements of the cam control member.

The mechanism is mounted on a table top or working surface 21 which may be conveniently positioned on a frame formed by welding or otherwise connecting upright legs 22 and horizontal stretchers 23 and 24. In the particular form shown in the drawings, the top 21 is supported above the main frame by spacer blocks 25 resting on corner plates 26, and it is retained by bolts 27. The top 21 is provided with a depressed portion 28 conveniently located adjacent one corner. As best shown in Fig. 5, a bearing housing boss 29 depends below an opening in the center of the portion 28, and in it are fitted spaced bearings 31 which rotatably support a vertical shaft 32, the upper end of which projects above the portion 28.

The upper end of the shaft 32 merges into and is integrated with a clamping block 33, which extends upwardly from the end of the shaft, and also outward from a shaft diameter. The end of the shaft, at a region just above the depression 28, is formed with a semicircular groove 34, which merges tangentially into horizontal grooves 35 and 36, formed on opposite faces of the block 33. The ends of the block 33 are provided with brackets 37 extending outwardly therefrom at right angles to the direction of the grooves 35 and 36, and these brackets are formed with aligned horizontal slots 38. The face of the block 33, above the groove 35, is formed with a hook 39, adapted to interengage with a similar hook 41 formed on a detachable clamping plate 42.

The plate 42 includes a vertical plane lower margin 43 formed with a longitudinal groove 44, with an angular portion 45 from which the hook 41 projects, and with a narrower vertical portion 46 adapted to enter between the brackets 37. When the hooks 39 and 41 are interengaged, the groove 44 is aligned with the groove 35 of the block 33, and these grooves can tightly encircle a section of tubing T, as is clearly shown in Fig. 6. A locking cam 47, provided with projecting trunnions 48 and an operating handle 49, is mounted between the brackets 37, the trunnions being loosely retained in the slots 38. When the handle 49 is swung counterclockwise, as viewed in Fig. 5, the arcuate ends of the cam 47 engage the inner faces of the block 33 and plate 42, thereby causing the plate 42 to pivot slightly about the fulcrum point between the hooks 39 and 41, and forcing the lower portion 43 of the plate 42 against the lower portion of the block 33, or against tubing positioned in the grooves 35 and 44.

It will be seen that the block 33 and plate 42 constitute relatively fixed and movable jaws of a pipe vise or clamp, wherein the tubing T may be securely retained against movement. The 75

grooves 35 and 44, in which the tubing is imprisoned, may be of semicircular contour, and have a radius substantially the same as that of the tubing to be worked upon, so that the tubing will be held against displacement, but at the same time will not be unduly crushed or deformed. When the handle 49 is swung in a clockwise direction, the cam 47 is disengaged from the surfaces of the block and plate, and the latter can then be detached. A lifting handle 51 is provided on the plate 42 to facilitate this operation. A relatively long operating handle 52 is secured to the outer face of the block 33 for rotating the shaft 32 about its own axis.

The recess 28 of the table top 21 is formed with a right angled depressed extension 54, in which are secured, by screws 55, a pair of tapered gibs 56, which provide a retaining bearing for a slide 57. The inner end of the slide 57 terminates in a transverse and upwardly extending flange 58, which is formed with a dovetail guide 59 to receive and retain a longitudinally slidable follower plate 61. As shown in Fig. 1, the plate 61 is normally retracted to the left by a spring 62, the ends of which are connected to a pin 63 on the table top, and a pin 64 (Fig. 6) on the end of the follower plate 61. At the start of a bending operation, the left hand end of the follower 61 abuts the rim of the depression 28, which serves as a positioning stop.

The outer face of the follower 61 is formed with a longitudinal arcuate groove 65, the leading portion of which is disposed opposite the groove 34 of the shaft 32. The trailing portion 35 of the groove 65 is adapted to face the groove 36 of the clamping block 33 at the completion of a bending operation, as illustrated in Fig. 6. It will be noted that the follower block 61 is longer than the block 33, so that, at the start of a bending operation, the extreme right end of the groove 65 slightly overlaps the groove 34. The slide 57 is herein shown as having been advanced or moved in its guides 56 toward the tubing T, to force the tubing tightly between the leading end 45 of the groove 65 and the shaft groove 34. As the shaft 32 is rotated from the Fig. 1 to the Fig. 6 position, pressure applied to the slide 57, and therefore to the block 61, progressively forces the tubing into the groove 34, while the trailing end of the tubing, and the follower block 61, move to the right.

It will additionally be seen from Fig. 6 that, at the end of a full return bend formation, the groove 36 of the block 33 faces the trailing portion 55 of the groove 65, and that it is slightly angularly disposed with respect thereto. The face of the block 33 containing the groove 36 is tapered with respect to the opposite face, so that the block 33 may be rotated slightly more than 180°. It has been found that the tubing tends to spring back at the bend, so that, if a bend of only 180° were made, the lengths would not be exactly parallel. Accordingly, provision is made for some overtravel to compensate for this effect. As the block 33 is swung to its maximum extent, the trailing portion of the tubing T is clamped between the groove 36 and the trailing portion of the groove 65, to restrain the tubing from further forward movement. During the last few degrees of rotation, adjacent tube lengths are brought slightly out of parallelism, and the metal at the bend proper is slightly drawn further. Upon separation of the grooves 36 and 65, the spring back effect enables the tube lengths to return to true parallel relation.

Means are provided to apply substantial pressure to the tubing to force it between the grooves 34 and 65, and to maintain the pressure until the bend is formed. The details are best illustrated in Figs. 2, 3, 4, and 5. A pneumatic ram 71 is bolted or otherwise secured to a bottom plate 72 of a frame including side rails 73 and a top rail 74, which in turn is affixed to the under side of the table top 21. The piston rod 75 of the ram extends upwardly through the plate 72, and its exposed portion has connected thereto a cross bar 76, adapted to abut adjustable stop screws 77 which are threaded into bracket arms 78, welded to the side rails 73.

A pair of bearing plates 81, welded to the top rail 74, are provided with aligned bearing apertures in which is mounted a shaft 82, which carries a bell crank lever 83. One arm 84 of the lever is coupled to the end of the piston rod 75 by means of a bifurcated yoke 85 threaded onto the end of the rod, and a pivot pin 86. The other arm 87 of the lever 83 is formed with a ball end positioned in a socket block 88, which is secured to the slide 57 by screws 89 (Fig. 1). An aperture 91 in the table top 21 permits the block 88 to slide back and forth with the slide 57, as the piston rod 75 is reciprocated. It will be readily understood that, as the piston rod is elevated, the slide 57 is forced toward the shaft 32, and when the rod is withdrawn, the slide 57 is retracted to clear the tubing T. The adjusting screws 77 limit the upward movement of the rod 75, and therefore the maximum pressure which can be exerted on the work, which pressure can obviously be controlled within very narrow limits.

A platform 93 is suspended beneath the table top 21 by means of posts 94 and bolts 95 entering blind tapped holes in the top. An air control valve 96 is mounted on the platform 93, to receive air from a supply source through a line 97, and deliver it to the ram 71 through a line 98. It may be pointed out here that the details of neither the valve 96 nor the ram 71 form any part of the present invention, as each device is a known article of commerce available in the United States. It will be sufficient to note that the valve 96 includes an actuating plunger 99, which may be depressed or released by movement of a lever 101 pivoted to the valve casing. When the plunger 99 is depressed, air may flow through the valve to the cylinder of the ram 71, thus elevating its piston rod 75, and when the plunger is released, the air supply through the line 97 is cut off, and the air in the ram 71 bleeds back through the valve to atmosphere.

The admission of compressed air to the ram 71 is controlled by the position of the shaft 32, through a cam 105 (Fig. 9), mounted on the lower end of the shaft. The cam comprises a concentric hub 106 formed with a segmental flange 107 having an upstanding peripheral rim 108 for the major portion of its length. The forward portion of the flange 107 is provided with a depending boss 109, which is drilled to provide a bearing for a pin 111 having an arcuate latch element or switch cam 112 on its upper end. The lower end of the pin 111 projects beyond the boss 109, to receive a lever 113, to the outer end of which is connected a spring 114 extending to a stud 115 on the hub 106. The spring 114 urges the latch 112 in a counterclockwise rotative direction, so that its tip normally abuts the hub 106 above the flange 107, to provide a small exposed surface of the flange in front of the latch.

A cam lever 116 is pivotally mounted on the

platform 93, and its free end is equipped with a depending roller 117 adapted to rest on the flange 107 in the notch formed between the end of the latch 112 and the hub 106. The lever 116 is normally urged to this position by a spring 118 extending from the midportion of the lever to a bracket 119 secured to the platform 93. The edge of the lever engages the outer end of the valve lever 101, and, in this position, the plunger 99 is extended, corresponding to a condition of release of air from the ram 71. A few degrees rotation of the shaft 32 causes the roller 117 to ride outwardly on the convex surface of the latch 112, thereby depressing the valve plunger 99 through the conjoint displacements of the levers 116 and 101. As the shaft continues to rotate, the roller 117 rides over the outer surface of the rim 108, retaining the valve 96 open, until the trailing edge of the rim 108 passes the roller.

It will be seen from Figs. 4 and 9 that the arc swept out by the cam 112 and rim 108 is less than 180°, and this diminution is determined by the diameter of the cam roller 117. The parts are so proportioned that, as the outer surface of the rim 108 completely clears the roller 117, the shaft 32 has rotated a full 180°. At this instant, the spring 118 pulls the lever 116 against the hub 106, and inside the rim 108, thereby enabling the valve plunger 99 to move outwardly automatically and release the air pressure in the ram 71. When the shaft 32 is restored to the starting position, the roller abuts the inner surface of the latch 112 to swing it outwardly about its pivot 111, thereby returning the lever 116 and latch 112 to their starting positions.

It has heretofore been noted that the pressure applied to the tubing between the shaft groove 34 and the leading portion of the follower groove 65 is substantial, and that these grooves are not truly semicircular in cross section. The grooves 35 and 44, and the grooves 36 and trailing portion of the groove 65, may be semicircular, as they engage straight portions of tubing. As a practical matter, it does no harm to make the groove 65 of the same contour throughout, as the manual pressure applied in the overtravel of the block 33, to set the bend, will not cause any appreciable deformation. The nature of the grooves 34 and 65 is best shown in Figs. 6 and 7.

Assuming a machine proportioned to bend 0.375" outside diameter steel tubing, it will be seen from Fig. 7 that the grooves 34 and 65 are so contoured as to increase the overall dimension of the tubing, in a right section taken through the bend, and in the horizontal plane. Similarly, the overall dimension is decreased in the vertical plane, and therefore the tubing may be considered to be slightly flattened, or made out-of-round, with the major axis in the plane of the coil. The dimensions given in Fig. 8, of $D+0.017"$ for the horizontal or major axis, and $D-0.040"$ for the vertical or minor axis, refer to tubing of the stated size and character, and these of course may be proportionately varied with non-ferrous tubing, or tubing of other diameter. In practice, it is feasible to lay out the contours as three centered arches, which may be followed with sufficient accuracy with a grinding wheel, and to blend the several contours into each other, and into the adjacent semicircular contours, so that continuous smooth curves are obtained.

At the beginning of a coil forming operation, the shaft 32 and die block 33 are swung clockwise to the position shown in Fig. 1, with the slide 57 and follower 61 in retracted positions.

The leading end of a length of tubing T is then pushed over the table top 21 and into engagement with the groove 35, and the detachable clamping plate 42 is then locked to the block 33 to secure the tubing an appropriate distance from its leading end. The portion of tubing immediately in back of the clamped section is then located between the leading tip of the groove 65, and that portion of the shaft groove 34 which directly merges into the groove 35.

As the operating lever 52 is swung counter-clockwise, the cam member 105 actuates the valve 96 to admit air to the ram 71, as heretofore described, thereby forcing the slide 57 and follower 61 against the tubing, and forcing the tubing between the grooves 34 and 65 to cause it to take substantially the cross sectional shape of the grooves 34 and 65. As the shaft 32 continues to rotate, the follower block 61 moves to the right, as shown in Fig. 6, and hence successive increments of the grooves 34 and 65 act as mating portions of a forming die through which the tubing is drawn. That portion of the tubing which constitutes the return bend proper is therefore progressively formed and wrapped into the groove 34, and it will be seen that the increment of tubing undergoing working at any instant is tightly clamped about its entire circumference.

As heretofore noted, the cam 105 is of such arcuate length as to release the cam roller 117 after 180° rotation, thus removing the pressure exerted on the tubing through the ram 71. The slight additional rotation which may be effected by the taper of the leading face of the block 33 sets the bend to compensate for resilience or spring-back effect. The clamping plate 42 is then disengaged by manipulation of the handle 49, and the tubing is freed from the block 33 so that the shaft 32 may be restored to starting position, preparatory to forming a successive bend.

It will be obvious that the principles of the invention are not restricted to forming full return bend coils, as bends of varying arcs may be made by suitable adjustment of the time of application of pressure. It will likewise be apparent that, in its broader aspects, the invention is not limited to the precise details of the mechanisms specifically illustrated and described. It is accordingly intended that the invention should be accorded a range of equivalents and scope commensurate with that expressed in the following claims.

I claim:

1. In a machine for bending tubing of circular cross section, a rotatable shaft formed with a circumferential groove, a clamping vise attached to the shaft and extending radially outward therefrom, said vise being formed with mating arcuate grooves adapted to secure tubing tightly therebetween and tangentially to the shaft groove, a portion of said vise being in substantially radial alignment with said shaft the maximum thickness of said portion being substantially equal to the diameter of said shaft, a follower positioned adjacent the shaft and movable both radially and tangentially with respect thereto, said follower being formed with a groove disposed tangentially to the shaft groove, said follower and shaft 70 grooves, in conjoint cross section, having an out-of-round curvilinear periphery, the major axis of said conjoint follower and shaft grooves being normal to the shaft and the minor axis thereof being parallel to the shaft, the dimension of 75

said grooves on said major axis being sufficiently greater than the normal outside diameter of said tubing and the dimension of said minor axis being sufficiently less than the normal outside diameter of said tubing to permanently flatten the bent portion of said tubing during the bending operation, and means for forcing the follower toward the shaft to clamp circular section tubing between the shaft and follower grooves and progressively bend and deform such tubing into said permanently flattened cross section as said shaft is rotated to bend the tubing.

2. In a bending machine, a working surface having a shaft rotatably mounted therein, said shaft extending above and below the surface, a circumferential groove formed in the shaft above the surface, a vise connected to the shaft to secure tubing therein and tangentially against the shaft groove, a slide and follower mounted on the surface for movement toward the shaft in a radial direction, said follower being slidably mounted on the slide for movement tangentially of the shaft, said follower being formed with a longitudinal groove adapted to cooperate with the shaft groove to grip tubing when the slide is moved toward the shaft, power means for moving the slide and follower toward the shaft, a cam control member mounted on the shaft below the surface, said member having a hub, a pivoted latch extending outwardly from the hub, and a dwell portion of limited arcuate length contiguous with the pivoted end of the latch, and a cam lever pivotally mounted below the surface for displacement by the latch and dwell portion of the cam, means governed by the cam lever for energizing the power means, the lever and cam being so related that the lever is positioned against the hub adjacent the latch to de-energize the power means at the initial starting position of a bending operation, the lever is displaced as the shaft is rotated to energize the power means, is released for return to de-energized position as the dwell portion clears the lever, and is restored to initial position when the shaft is rotated in a reverse direction to the starting position.

3. A machine as defined in claim 1 in which the portion of said vise in substantially radial alignment with said shaft is provided with grooves in the opposite faces thereof such grooves being at a slight angle to each other and in which the opposite faces of said portion are at a slight angle to each other whereby the shaft may be rotated more than one hundred eighty degrees during the bending operation to set the bend at a radius substantially equal to the radius of the groove in the shaft.
